DISPOSABLE GLUE POT LINERS

Charles M. Lask, ½ Labor Saving Devices, 1414 S.
Michigan Ave., Chicago, Ill. 60605

Filed Dec. 15, 1969, Ser. No. 20,492

Term of patent 14 years

Int. Cl. D5—99

U.S. Cl. D59—2

FIG.1

FIG.2

FIG.3

FIG.4

FIG.5

FIG.6

FIG. 1 is a top plan view of a disposable glue pot liner showing my new design;

FIG. 2 is a view looking in the direction of the arrows 2-2 of FIG. 1;

FIG. 3 is a view looking in the direction of the arrows 3-3 of FIG. 1;

FIG. 4 is a view looking in the direction of the arrows 4-4 of FIG. 2;

FIG. 5 is a view looking in the direction of the arrows 5-5 of FIG. 2; and

FIG. 6 is a bottom plan view thereof.

I claim:

The ornamental design for a disposable glue pot liner, as shown.
